UNITED STATES PATENT OFFICE

165,501

DECK OF PLAYING CARDS

Evert Zeeven, New York, N. Y.

Application January 4, 1951, Serial No. 13,662

Term of patent 14 years

(Cl. D34—13)

To all whom it may concern:

Be it known that I, Evert Zeeven, a subject of the Kingdom of Holland, residing in the Borough of Manhattan, city and State of New York, have invented a new, original, and ornamental Design for a Deck of Playing Cards, of which the following is a specification, reference being had to the accompanying drawings, forming part thereof.

Figs. 1 to 4 inclusive are plan views of the faces of the cards in a deck of playing cards, showing my new design.

The cards are of no appreciable thickness and the backs thereof have a plain or conventional appearance.

I claim:

The ornamental design for a deck of playing cards, substantially as shown and described.

EVERT ZEEVEN.
